CAR ROOF

Garth G. Gilpin, Riverside, Ill., assignor to P. H. Murphy Company, New Kensington, Pa., a corporation of Pennsylvania

Application September 17, 1936, Serial No. 101,215

11 Claims. (Cl. 108—5.4)

My invention relates to metal car roofs. One of its principal objects is to conform the upper surface of the roof as closely as practicable to the established tunnel clearance outline and at the same time make the roof as thin as practicable so as to give the car a maximum loading capacity. Another principal object is to adapt the carline spacing to suit the requirements of the lading. Another object is to provide for the use of separate carline members in lieu of an integral or continuous carline. Another object is to facilitate the work of building and assembling the car roof and to provide for the use of preassembled units which may be designed to better advantage than roofs wherein the sheets and carlines are continuous from side plate to side plate of the car. The invention consists in the construction hereinafter described and claimed and particularly in the parts hereinafter described and claimed.

In the accompanying drawings wherein like reference numerals refer to like parts wherever they occur,

Fig. 1 is a plan view of a car roof embodying my invention;

Fig. 2 is a similar view illustrating a modified form of the invention;

Fig. 3 is a plan view of a portion of the car roof shown in Fig. 1;

Fig. 4 is a vertical cross section on the line 4—4 in Fig. 3;

Fig. 5 is a fragmentary vertical cross section through the eaves portion of the roof shown in Fig. 4;

Fig. 6 is a fragmentary vertical cross section on the line 6—6 in Fig. 3;

Fig. 7 is a fragmentary longitudinal section on the line 7—7 in Fig. 3;

Fig. 8 is a fragmentary vertical longitudinal section on the line 8—8 in Fig. 3;

Fig. 9 is a fragmentary vertical longitudinal section on the line 9—9 in Fig. 1;

Fig. 10 is a section similar to Fig. 4 through the modified roof construction shown in Fig. 2;

Fig. 11 is a section similar to Fig. 5 through the eaves portion of the modified roof construction;

Fig. 12 is a section similar to Fig. 6 through said modified roof construction.

The present roof comprises series of units made up of sheets and carline members, which units are united together and to the side plates of the car. There are two types of units hereinafter referred to as the side units A and the ridge units B, respectively. As shown in Fig. 1, there are four side units and two ridge units, each

roof unit extending one-half the length of the roof.

Each of the side units A comprises a roof sheet 1 with one or more carline members 2 secured to the under side thereof, as by welding. The eaves end of the roof sheet of each side unit and its carline members are flanged downwardly, as at 3, and secured flatwise, as by rivets 4, to the outer face of an upstanding leg of a side plate 5 of the car. As shown in Fig. 9, the remote ends of adjacent side sheets are flanged downwardly and secured flatwise, as by rivets 6, to the outer faces of the end plates 7 of the car. As shown in Fig. 7, the adjacent margins of adjacent side sheets 1 are secured together and to the adjacent carline members 2 of one of said sheets, preferably by welds 8. The inner end margin of the roof sheet of each side unit is bent downwardly to form a downturned flange 9 adapted to be secured to the longitudinal margin of an adjacent ridge unit B.

The roof sheet 10 of each ridge unit B is a flat rectangular horizontally disposed sheet with downturned flanges 11 along its longitudinal margins. Each ridge sheet 10 has one or more carline members 12 secured to the under side thereof, as by welding. Adjacent margins of adjacent ridge sheets 10 are secured together and to the adjacent carline member 12 of one sheet, preferably by a transverse weld 13 that joins the side sheet welds 8 to form a continuous transverse weld. The remote ends of adjacent ridge sheets are flanged downwardly and secured by the rows of rivets 6 to the end plates of the car. The longitudinal flanges 11 of the ridge sheets 10 abut flatwise against the downturned flanges 9 of the side sheets 1 and are secured thereto preferably by longitudinal lines of welds 14 and 15 at the top and bottom thereof, thereby forming rigid longitudinal seams that function as purlines.

The carline members 12 illustrated in Fig. 8 are channel-shaped and extend, transversely of the car, from one longitudinal downturned flange 11 of the ridge sheet 10 to the other longitudinal downturned flange 11 thereof. Such carline member is welded to the under side of the ridge roof sheet by welds 16 that extend transversely of the roof and its ends are secured to the flanges 11 by vertical lines of welds 17. The carline members 2 of the side sheets 1 are similarly welded, as at 18 and 19, at their tops and inner ends, respectively. Obviously, the carline members may be of any other suitable cross-

sectional shape, or in the form of ribs pressed in the roof sheets.

The units hereinbefore described may be made of various sizes and may include one or more carline members for each unit, as determined by convenience of manufacture, shipment and assembly. In their assembled relation, the carline members of transversely alined units may be disposed either in alinement with one another, as shown in Fig. 1, or offset longitudinally of the car, as shown in Fig. 2. In case of such offsetting, it is preferable, as shown in Fig. 12, to incorporate a reinforcing member 20 in the longitudinal seams between the ridge sheets and the side sheets in order to coordinate the side carline members and the ridge carline members into a simple beam or structure with ends resting on the side plates, as when the carline members are alined.

The running board 21 consists of a plurality of spaced parallel boards that rest flatwise upon the top of the ridge sheet with the spaces between said boards filled with a waterproof compound 22. The running board is secured to the roof preferably by inverted channel shaped straps 23 that straddle said board and have outstanding base flanges that are welded to the tops of the ridge sheets. As shown in Fig. 7, the top of the running board is channeled, as at 24, from side to side to bring the tops of the straps flush with the upper surface of the running board.

By making the ridge units separate from the side units, the designer is afforded great latitude in the shape and dimensions of the carline members of the different units as well as in the spacing of such carline members. Thus, although it is customary to increase the depth of carlines from eaves to ridge, it is practicable in my construction to avoid such increase of depth and to make the lower face of the carline member of the ridge unit horizontal and parallel with the horizontal roof sheet. In fact, by using carlines of suitable cross-section and in sufficient number, it is practicable to make a roof of less depth at the ridge than has heretofore been practicable with inside carlines.

It is noted that the ridge sheets 1 are flat and horizontal and that the running board 21 is secured flatwise thereon. By this arrangement, the ridge sheets may be placed at such position that the upper surface of the running board lies immediately below the established clearance line for tunnels and bridges. The ridge sheets, therefore, may be made of such width that their longitudinal margins will fall just short of the established clearance outline C; and, as shown in Fig. 4, the side sheets may extend from this point to the side plate in two straight reaches with a break between them to correspond with the established clearance outline. Thus, the close approximation of the upper surface of the roof to the clearance outline from side plate to side plate, coupled with the thinness or small depth of the roof structure, especially when the carline members are spaced to accommodate special lading, increase the capacity of the car and make it practicable to utilize the full capacity of the car for lading. As shown in Fig. 10, the side sheets may extend in single straight stretches from the ridge sheets to the side plates, thereby eliminating press work in the manufacture of such sheets.

It is an advantage of my construction that the same side sheets may be used with ridge sheets of different widths so as to meet the requirements of cars of different widths.

75 It is noted as a great advantage of my inven-

tion that it permits the ridge carline members to be spaced at such distances apart as may be best adapted for the lading.

What I claim is:

1. A car roof comprising a series of roof sheets 5 secured together at their sides by transverse seams and secured to the substructure at the eaves, and an intermediate series of sheets secured together by transverse seams and secured to the adjacent side sheets by longitudinal seams, 10 said sheets having downturned flanges along their adjacent longitudinal margins, and separate carline members substantially coextensive with the respective sheets disposed transversely of the car and welded to the respective sheets and 15 to the downturned longitudinal flanges thereof.

2. A car roof comprising a series of roof sections along each side of the roof and a series of roof sections covering the space between said side sections, each of said sections comprising a 20 sheet having a separate carline member substantially coextensive therewith and welded to the under surface thereof, the side sections being welded to the intermediate sections in such manner that the carline members of transversely 25 alined roof sections, together with the metal between their ends, are united into simple beams which reach from side plate to side plate of the car.

3. A car roof comprising side plates, a series of 30 roof sheets secured together by transverse welds and secured to said side plates at the eaves and having downturned flanges along their inner edges, and intermediate series of sheets having 35 downturned flanges along their side margins, said intermediate sheets being secured together by transverse welds and secured to the adjacent side sheets by longitudinal welds.

4. A car roof comprising a series of roof sheets secured together by transverse welds and secured 40 to the substructure at the eaves and having downturned flanges along their inner edges, an intermediate series of sheets having downturned flanges along their side margins, said intermediate sheets being secured together by transverse 45 welds and secured to the adjacent side sheets by longitudinal welds, and separate carline members substantially coextensive with the respective sheets disposed transversely of the car and welded to the lower surfaces of the respective sheets 50 and to the downturned flanges thereof.

5. A car roof comprising a series of roof sheets secured together by transverse welds and secured to the substructure at the eaves and having 55 downturned flanges along their inner edges, an intermediate series of sheets having downturned flanges along their side margins, said intermediate sheets being secured together by transverse welds and secured to the adjacent side sheets by longitudinal welds, and separate carline members substantially coextensive with the respective sheets disposed transversely of the car and welded to the lower surfaces of the respective sheets and to the downturned flanges thereof, the spacing of the carline members of said intermediate 60 series of sheets being different from the spacing of the carline members of the other series of sheets.

6. A car roof comprising a series of roof sheets secured together by transverse welds and secured 70 to the substructure at the eaves and having downturned flanges along their inner edges, an intermediate series of sheets having downturned flanges along their side margins, said intermediate sheets being secured together by transverse 75

- welds and secured to the adjacent side sheets by longitudinal welds, and separate carline members substantially coextensive with the respective sheets disposed transversely of the car and 5 welded to the lower surfaces of the respective sheets and to the downturned flanges thereof, the carline members of said intermediate series of sheets being offset with respect to the carline members of the other series of sheets.
- 10 7. A car roof comprising side plates, side series of roof sheets secured together by transverse seams and secured to said side of plates at the eaves and provided along their longitudinal inner edges with depending flanges, 15 an intermediate series of sheets secured together by transverse seams and provided along their longitudinal edges with depending flanges, and welds uniting together the flanges of said side and intermediate sheets.
- 20 8. A car roof comprising side series of roof sheets secured together by transverse seams and secured to the substructure at the eaves and provided along their longitudinal inner edges with depending flanges, an intermediate series of 25 sheets secured together by transverse seams and provided along their longitudinal edges with depending flanges, plates interposed between the flanges of the side and intermediate sheets, and welds uniting together the flanges of said side and 30 intermediate sheets.
9. A car roof comprising side series of roof sheets secured together by transverse seams and secured to the substructure at the eaves and provided along their longitudinal inner edges with
- depending flanges, an intermediate series of sheets secured together by transverse seams and provided along their longitudinal edges with depending flanges, welds uniting together the flanges of said side and intermediate sheets, and 5 separate carline members disposed transversely of the car substantially coextensive with the respective sheets and welded to the lower surfaces of the respective sheets and to the flanges thereof.
- 10 10. A car roof comprising metal roof sheets 10 having flat horizontally disposed ridge portions, and a running board comprising a plurality of spaced parallel boards resting flatwise to said ridge portions, waterproof material filling the spaces between said boards, and metal straps 15 extending across said boards with their ends welded to said roof sheets.
11. In a railway car, spaced frame members, side series of sheets secured together at their sides by seams and secured to said frame members at their outer ends, and an intermediate series of sheets secured together by seams, said side and intermediate sheets having inturned flanges along their adjacent margins which abut against each other flatwise without overlapping 20 and are welded together to form stiffening ribs, and separate members substantially co-extensive with the respective sheets disposed transversely of said frame members and welded to the inner surfaces of the respective sheets with their ends 25 abutting against and welded to the inturned marginal flanges thereof.

GARTH G. GILPIN.
